UNITED STATES PATENT OFFICE.

LOYAL C. TABER, OF DANFORTH, ASSIGNOR TO WOOD, TABER & MORSE,
OF EATON, NEW YORK.

TRACTION-ENGINE.

SPECIFICATION forming part of Letters Patent No. 334,623, dated January 19, 1886.

Application filed October 19, 1885. Serial No. 180,328. (No model.)

To all whom it may concern:

Be it known that I, LOYAL C. TABER, of Danforth, in the county of Onondaga, in the State of New York, have invented new and 5 useful Improvements in Traction Engines, of which the following, taken in connection with the accompanying drawings, is a full, clear, and exact description.

This invention relates to traction-engines 10 having the propelling power transmitted to all of the carrying-wheels, and has special reference to the engine for which I have obtained Letters Patent of the United States No. 294,930, dated March 11, 1884, upon which my present invention is a specific improvement 15 designed to overcome certain defects, as herein-after explained.

Referring to the annexed drawings, Figure 20 I is a side elevation of a traction-engine embodying my improvements. Fig. II is a front end view of the same. Figs. III, IV, and V are detail views of the compensating-gears which are applied to both of the carrying-axles; and Fig. VI illustrates modifications of 25 the devices for maintaining the gear of the flexible or oscillatory counter-shaft in engagement with the compensating-gear on the axle of the forward carrying-wheels.

Similar letters of reference indicate corresponding parts.

A represents the boiler of the engine mounted on the axles B B' of the carrying-wheels W W, as hereinafter described. The rear end of the boiler I usually support by plates p, bolted 35 to the sides of the water-jacket A' of the firebox, which plates are formed with bearing-boxes in which the rear axle is journaled. I do not, however, limit myself to this particular connection of the boiler with the hind 40 carrying-axle, inasmuch as the same is susceptible of many modifications, and does not affect the essence of my present invention.

The forward axle, which constitutes the steering-axle, is pivoted at its center, the pivot in 45 this case being represented in the form of a hollow post, K, rigidly secured to the bottom of the boiler-shell, and having its lower end of the shape of a segment of a sphere, and stepped in a corresponding socket, b, on the 50 bed or saddle I, on which the forward axle, B', is journaled.

C denotes the driving-shaft of the engine. The engine may be of any suitable and well-known construction, and its illustration is therefore omitted here.

In order to transmit from the driving-shaft 55 C to the four carrying-wheels W a propelling power with equitable motion respondent to the various speeds required of the several wheels in traveling around curves, I provide each of the carrying-axles B B' with a compensating-gear, R, consisting of the gear-wheel R, mounted loosely on the axle, and having pivoted in it pinions f f, arranged with their axis radial to the axis of the wheel 60 R, and engaging with annular racks g g on the adjacent sides of disks S S, held against opposite sides of the wheel R, one of said disks being rigidly secured on the axle and the other disk being integral with the hub 65 of one of the carrying-wheels W, which latter is loosely mounted on the axle, the other wheel W being rigidly attached to the opposite end of the axle.

For the construction and combination of 70 the aforesaid parts reference should be had to Figs. III, IV, and V of the drawings. These compensating-gears are capable of transmitting propelling power to both axles, and at the same time permit of an equitable movement of all the four wheels while traveling 75 around curves.

To the two compensating-gears R R synchronous motion is transmitted by the following instrumentalities: On the driving-shaft C 80 is fastened a pinion, D', and on trunnions or gudgeons secured to the side of the boiler is mounted a train of gears, E F F F F, the first of which gears meshes in the pinion D', and on the side of the last of said gears and integral therewith is a pinion, G, which meshes in the compensating-gear R of the hind axle, B, 85 as illustrated in Fig. I of the drawings.

On a trunnion rigidly attached to the forward portion of the boiler are journaled side 90 by side a pinion, N', and a gear-wheel, O, cast in one piece. The gear-wheel O meshes in the gear E, and the pinion N' engages a pinion, N, which is attached to the end of a counter-shaft, L, the opposite end of which carries 95 a pinion, P, which meshes in the compensating-gear R of the forward axle, B'. In order

to maintain the pinions of the said counter-shaft in engagement with the pinion N' and compensating-gear R during the oscillations of the axle B incident to the travel of the engine over uneven roads and around curves, it becomes necessary that the counter-shaft L shall be allowed a similar or corresponding oscillatory movement, so as to accommodate itself to the axle, and this I have heretofore 5 accomplished by dividing the axle transversely in the center of the hollow pivoting post K , and providing it thereat with a universal joint, and supporting one of the end sections of the said shaft in a box, e , secured to the axle-bed 10 I , so as to cause said portion of the shaft to follow the axle in its oscillatory movement and maintain the pinion P in engagement with the compensating-gear R , the other end section of the shaft being journaled in a box, n , 15 which is secured stationary on the boiler and parallel with the driving-shaft C and journal of the pinion N' , and holds the pinion N in gear with the pinion N' .

The location of the universal joint in the 20 center of the pivot-post K , I have found objectionable for several reasons, viz: first, it necessitates undue enlargement of the post K and a corresponding enlargement of the step of said post in the socket b , which latter produced undue friction when turning the axle on its pivot; secondly, it rendered the adjustment of the universal joint very difficult; and, thirdly, the oscillatory end section of the counter-shaft was liable to become bound in the 25 opening in the side of the post K , through which said shaft-section projects. To overcome these defects and attain other advantages, I make the counter-shaft L flexible by forming it of two end sections and an intermediate section coupled to the end sections by suitable universal joints, d , said joints being remote from or outside of the pivot-post K , and the end sections being carried, respectively, parallel with the axle and driving-shaft 30 in a manner similar to that shown in my prior patent hereinbefore referred to.

Inasmuch as the jointing of the counter-shaft outside of the pivot of the axle causes a differential longitudinal movement of the axle 35 and oscillatory part of the counter-shaft when oscillated, the pinion P is carried laterally during the aforesaid movement, and in order to maintain said pinion in engagement with the compensating-gear R , I either make the latter wide enough to allow the pinion to slide 40 laterally thereon, as represented in Fig. I of the drawings, or mount said pinion loosely on the counter-shaft, so as to allow it to slide laterally on said shaft and compel it to rotate 45 therewith by the well-known spline-and-feather connection of the same.

A clutch-arm, l , projects from the portion of the axle-bed I on which the vibratory end of the counter-shaft is journaled, and this arm 50 engages with a circumferential flange, u , on the hub of the pinion P , as illustrated in Fig. VI of the drawings.

Having described my invention, what I claim as new, and desire to secure by Letters Patent, is—

1. In a traction-engine, the combination, with the four carrying-wheels and their axles, of two compensating-gears, one on each axle, an oscillatory counter-shaft supported at its oscillatory end in a bearing mounted on the forward or steering axle, and a train of gears extending from the driving shaft to the two compensating-gears, all combined to transmit to all the carrying-wheels propelling power respondent to the various speeds of motion required of the several wheels in traveling around curves, substantially as set forth. 75

2. The combination, with the forward carrying-wheels and their axle, of a compensating gear on said axle, an oscillatory counter-shaft carried at its oscillatory end by a bearing mounted on said axle, a laterally movable gear on the counter-shaft meshing in the compensating-gear, and gears for transmitting motion from the driving-shaft to the counter-shaft, substantially as described and shown. 80

3. In combination with the driving-shaft, pivoted axle, and traction-wheels on the latter, a gear mounted on said axle, a flexible counter-shaft composed of a section carried parallel with the axle, a section carried parallel with the driving-shaft, and an intermediate section coupled to the other sections by universal joints, and gears for transmitting motion from the driving-shaft to the gear on the axle through the medium of the counter-shaft, substantially as set forth and shown. 95

4. In combination with the driving-shaft, pivoted axle, and traction-wheels on the latter, a gear mounted on said axle, a flexible counter-shaft having its joint remote from the pivot of the axle, and gears on said counter-shaft engaging with the gear on the axle, and with gears interposed between the driving-shaft and counter-shaft, substantially as set forth. 105

5. In combination with the driving-shaft, pivoted axle, and traction-wheels on the latter, a gear mounted on said axle, a flexible counter-shaft carried by a support on the axle to follow the same in its oscillatory movement, a gear sliding on the counter-shaft and held in engagement with the gear on the axle, and a gear on the counter-shaft engaging with gears interposed between the driving-shaft and counter-shaft, substantially as and for the purpose set forth. 115

In testimony whereof I have hereunto signed my name and affixed my seal, in the presence 120 of two attesting witnesses, at Syracuse, in the county of Onondaga and State of New York, this 16th day of October, 1885.
